LOCK NUT

Joseph F. Ebert, Hollis, N. Y., assignor, by mesne assignments, to Smaller War Plants Corporation, New York, N. Y., a corporation of the United States

Application August 26, 1943, Serial No. 500,044

6 Claims. (Cl. 10—86)

This invention relates to lock-nuts and the manufacture thereof.

In the application of William Ruthven, Serial No. 472,333, filed January 14, 1943, is disclosed a nut comprising a metallic polygonal body or bottom having a central threaded aperture and a polygonal socket composed of connected flat wall portions integral with the bottom. A locking member of complementary configuration to the socket is received therein and has an opening therethrough aligned with the bottom aperture. Each wall portion has an integral tapered tab, the base of which is co-extensive with the top edge of the wall portion and each tab is bent inwardly over the locking member to hold the latter in the socket.

An object of this invention is to embody the nut structure above described of powdered metal.

A further object of this invention is a highly efficient and inexpensive procedure of producing such nuts at a high rate.

In the production of nuts according to this invention, a charge of powdered metal is subjected to pressure by suitably shaped dies to produce a shell consisting of a perforated polygonal body portion and a connected series of wall portions defining a polygonal socket with each wall portion being integral with the body portion and having a tapering tab extending from the edge thereof. A thread is cut in the surface defining the body portion aperture, after which the shell is subjected to heat treatment under conditions suitable to fuse the compressed powdered metal into a unitary mass. A locking member complementary in shape to the socket is introduced therein, after which the tabs are turned inwardly over the member to lock it in the socket. According to this procedure the shell, together with its wall portions equipped with tapering tabs, is produced in a one-operation procedure.

Other objects, novel features and advantages of this invention will become apparent from the following specification and accompanying drawing, wherein:

Fig. 1 is a plan view of a self-locking nut embodying the invention with a bolt inserted and serving to hold together two plates;

Fig. 2 is a section on the line 2—2 of Fig. 1;

Figs. 3 and 4 are vertical sections of an apparatus for pressing the powdered charge into the form of a shell and illustrate such procedure;

Fig. 5 is an elevation partly in section of the shell produced by the apparatus of Figs. 3 and 4;

Fig. 6 is a similar view of the completed shell, and

Fig. 7 is a section of the completed nut taken substantially on the line 7—7 of Fig. 1.

As illustrated in Figs. 1, 2, 5 and 6, a nut produced according to this invention comprises a metallic hexagonal body or bottom 1 having a central threaded aperture 2 and a hexagonal socket composed of connected flat wall portions 3 integral with said bottom. A resilient insert 4 of complementary configuration to the socket is received therein and has an opening 5 therethrough aligned with the axis of the thread of the aperture 2 and of a diameter less than the major diameter of the aperture thread. Each wall portion 3 has an integral arcuate extension or tab 6, the base of which is co-extensive with the top edge of the wall portion. The tabs 6 are bent inwardly over the insert to hold it in the socket and the taper of each tab is such that when folded in it does not interfere with the adjacent tab. Together the tabs provide a substantially continuous clamping flange along the rim of the socket to retain the insert 4 securely in place and prevent ejection of the insert from the socket upon insertion of a bolt into the insert through the threaded aperture 2. The end surface 7 constitutes the face of the nut. As shown in Fig. 2, a bolt 8 passes through two or more plates 9 or the like to be held together and is first entered into the bottom aperture 2, after which it passes through the bore 5 of the insert 4 in the surface of which it embosses its thread. The surface 7 thus constitutes the abutting face of the nut when the nut is drawn home. The resilient insert 4 is shown herein as being non-metallic, but may be metallic.

The procedure of constructing a shell is illustrated in Figs. 3 and 4. In these figures, 10 designates a fixed member which supports a die block 11 having a cavity 12 of hexagonal cross-section. In the bottom of the cavity 12 is a hexagonal block 13 snugly fitting the cavity but movable therein and normally resting on the member 10. A rod 14 extends from the lower end of the block 13 through the member 10 and a pin 15 extends from the upper end of the block a short distance above the die block 11.

A plunger 16 is carried by a movable member 17 and means, not shown, are provided for effecting movement of the member 17 toward and away from the member 10. The main portion of the plunger 16 is of hexagonal cross-section and is of proper size snugly to fit the cavity 12. The lower portion of each face of the plunger 16 is cut away so that when the punch is inserted in the die the space between each plunger face and each die

face is of the same shape as a wall portion 3 and a tab 6. The exposed length of the plunger 16 is less than the distance from the top of the die block 11 to the top of the abutment block 13 so that when the punch is fully inserted in the die, the bottom face of the punch is spaced from the top face of the abutment block. Also, the plunger 16 is provided with a recess 16a to receive the pin 15.

In the production of a nut, a charge of powdered metal is introduced into the cavity 12 with the bottom block in its lowermost position with

applicant's co-pending application, Serial No. 474,423, filed February 2, 1943.

I claim:

1. The method of producing a self-locking nut which comprises forming a charge containing powdered metal under pressure into a shell consisting of a centrally perforated polygonal body portion and a connected series of wall portions defining a polygonal socket with each wall portion being integral with said body portion, providing a thread in the surface defining said body

socket having a continuous surface bottom except for said aperture and a continuous wall, said wall portions terminating in tapering integral tabs, and a polygonal resilient insert in said socket of complementary size and shape to said socket to prevent relative rotation of said socket and insert, each tab being inturned over said insert without interference with an adjacent

tab and providing a substantially continuous clamping flange for said insert along the rim of said socket to retain the insert in the socket, said base and wall portions and tabs comprising powdered metal pressed and sintered into a composite mass.

JOSEPH F. EBERT.
